(57) **CLAIM**

The ornamental design for a sheet cube holder with lenticular side panels, as shown and described.

DESCRIPTION

This application claims the benefit of U.S. application Ser. No. 60/957,653, filed Aug. 23, 2007, and such prior application is incorporated by reference herein.

FIG. 1 is a front top perspective view of the invention, with a sheet cube therein shown in broken lines and which forms no part of the invention;

FIG. 2 is a front top perspective view of the invention, as in FIG. 1, but without the sheet cube therein;

FIG. 3 is a plan view of the invention;

FIG. 4 is a side elevational view of the invention;

FIG. 5 is a bottom plan view of the invention;

FIG. 6 is a bottom perspective view illustrating the bottom and opposite sides of the invention as compared with the sides shown in FIG. 1; and,

FIG. 7 is an enlarged horizontal sectional view taken as a slice along the line 7—7 of FIG. 4.

The broken lines showing a sheet cube in FIG. 1 and the pattern in the bottom surface shown in FIGS. 3, 5, and 6 illustrate environmental matter and form no part of the claimed design.

The cutaway portions shown on opposite sides in FIG. 7 are merely for ease of illustration in order to allow the view to fit on one drawing sheet and do not represent a departure from the overall shape and appearance of the claimed design as shown in the other drawing figures.
